UNITED STATES PATENT OFFICE.

HARRY DIXSON, OF PELLA, IOWA, ASSIGNEE TO BOLSCREEN COMPANY, OF PELLA, IOWA.

GUIDE TRACK FOR SCREEN CONSTRUCTION.

Application filed February 19, 1927. Serial No. 169,555.

My invention has to do with a guide track for a rolling window screen or the like where-
in the screen may be threaded into the guide
track after it is accidentally removed there-
from, by simply moving the screen towards
5 rolled up position.

Still a further object is to provide a track
guide having a tubular portion provided with
a slot extending lengthwise thereof and the
10 side edges of a screen having thickened por-
tions thereon received in said tubular portion,
the slot in the tubular portion being of less
diameter than the thickness of the retaining
members or thickened portions which are
15 adapted to travel within the tubular portion
of the guide track and at the same time to pro-
vide the tubular portion of the guide track
with a portion or part where the material or
walls of the tubular portion are spread apart
20 a greater distance than the width of said slot
thereby defining an enlarged opening so that
if the side edges and thickened portions of
the screen are accidentally withdrawn from
the guide track through the narrow slot, they
25 may reenter the guide track through the en-
larged opening and thereafter the side edges
of the screen travel up and down within the
tubular portion of the guide track.

With these and other objects in view, my
30 invention consists in the construction, ar-
rangement and combination of the various
parts of my guide track for screen construc-
tion, whereby the objects contemplated are at-
tained, as hereinafter more fully set forth,
35 pointed out in my claims, and illustrated in
the accompanying drawings, in which:

Figure 1 is a perspective view of a portion
of my guide track with the enlarged opening
formed therein and illustrating the screen as
40 it reenters the guide track.

Figure 2 is a side view illustrating the slot
in the track as well as the enlarged opening
together with a screen casing or housing in
communication with the upper end of the
45 track itself.

In the accompanying drawings I have used
the reference numeral 10 to indicate generally
a sheet metal casing in which may be mounted
a rolling window screen 12. The screen 12
50 passes out of the casing 10 through a slot
opening 14 formed in the casing 10.

The screen has adjacent its side edges a plu-
rality of clips 16 which may be referred to as
thickened portions. The clips 16 are com-
55 paratively large and form retaining members

for the side edges of the screen when traveling
in the guide tracks as will hereinafter be more
fully set forth.

The side edges of the screen 12 as well as
the clips 16 are designed to travel in guide
tracks A. The guide tracks A as illustrated
in the drawings are formed of a single piece of
metal bent upon itself to define a fastening
flange 18 formed with slot openings 20 for
receiving screws or the like whereby the track
A may be mounted upon an ordinary window
frame or casing.

The track A includes a tubular guide por-
tion 22 having the free ends of its walls spaced
apart a slight distance for forming a narrow
slot 24. The slot 24 extends lengthwise of
the guide track A. As illustrated in the
drawings the tubular guide portion 22 is
formed with a pair of flat flanges 26 which are
spaced apart by the slot 24. The screen 12
travels between the flanges 26.

The clips 16 are of greater size than the
normal width of the slot 24 so that as a matter
of fact, the clips 16 serve to retain the side
edge of the screen 12 within the track A. The
tubular portion 22 will, of course, spread
apart a little distance so that the width of the
slot 24 may be increased when undue pressure
is exerted against the screen 12 and when this
occurs, the side edge of the screen together
with the clips 16 will pass through the slot 24
as illustrated by the reference character B.

The tubular portion 22 which serves to
guide the side edges of the screen is some-
what resilient. As a result of this resiliency
the slot in the tubular portion will give or
spread rather than mutilate or tear the clips
16 from the side edge of the screen 12 when
undue pressure is applied against the screen.

Normally, however, the slot 24 does not al-
low the clips 16 to pass therebetween. In
order to have the side edges of the screen 12
and the clips 16 pass back into the guide
track after they have been pulled accidentally
from the guide portion 22, I provide an en-
larged opening 28 which is formed by spread-
ing the walls of the tubular portion 22 a
greater distance apart than the normal dis-
tance of the width of the slot 24.

The opening 28 is large enough to permit
the screen to rethread into the guide track A
with the clips 16 passing into the tubular
portion 22 through the opening 28. It may
here be mentioned that after the screen and
its thickened portions or clips have been
110

threaded into the guide track A, they will travel up and down within the tubular portion 22.

When the screen is accidentally pulled 5 from its guide track it usually has a portion of the screen still remaining in the guide track and when the screen is rolled up, the punched out portion as at B will pass into the tubular portion 22, through the opening 28 10 and then when the screen is withdrawn or pulled down, the entire side edge of the screen will pass into the tubular portion 22 below the opening 28.

It will be noted that the opening 28 is 15 formed by simply spreading the walls of the guide track A a short distance and that the opening is hardly noticeable and will not in any way interfere with maintaining a fly tight screen connection between the guide 20 track and the side edges of the screen.

Some changes may be made in the construction and arrangement of the parts of my device without departing from the real spirit and purpose of my invention, and it is 25 my intention to cover by my claims, any modified forms of structure or use of mechanical equivalents, which may be reasonably included within their scope.

I claim as my invention:

30 1. A guide track for a flexible roll screen having a tubular portion provided with a slot extending lengthwise thereof for receiving the side edge of the screen and allowing it to travel in the guide track as it is rolled up 35 and down, the material of said tubular portion for a part of its length being spread apart a greater distance than the width of said slot defining thereby an enlarged opening, whereby if the side edge of the screen normally

traveling in said track is accidentally withdrawn from the guide track, it may travel back into the guide track through said enlarged opening as the screen is rolled up. 40

2. A guide track for a flexible roll screen having a tubular portion provided with a slot extending lengthwise of the guide track for receiving the side edge of the screen and allowing it to travel in the guide track as it is rolled up and down, the material of said tubular portion at points spaced from the ends thereof being spread apart a greater distance than the width of said slot defining thereby an enlarged opening whereby if the side edge of a screen normally traveling in said track is accidentally withdrawn from the guide track it may automatically travel back into the guide track through said enlarged opening as the screen is rolled up. 45

3. A guide track for a flexible roll screen having a tubular portion provided with a slot extending lengthwise of the guide track for receiving the side edge of the screen and allowing it to travel in the guide track as it is rolled up and down, the material of said tubular portion at a point spaced from the upper end thereof being spread apart a greater distance than the width of said slot defining thereby an enlarged opening whereby if the side edge of a screen normally traveling in said track is accidentally withdrawn from the guide track it may automatically travel back into the guide track through said enlarged opening as the screen is rolled up, the upper half of said enlarged opening having sides inclined towards each other. 50

Des Moines, Iowa, February 1, 1927.

HARRY DIXSON.
